UNITED STATES PATENT OFFICE.

ROBERT E. ALEXANDER, OF NIAGARA, PENNSYLVANIA.

MACHINE FOR UPSETTING AND STRETCHING TIRES.

SPECIFICATION forming part of Letters Patent No. 256,944, dated April 25, 1882.

Application filed November 19, 1881. (Model.)

To all whom it may concern:

Be it known that I, ROBERT E. ALEXANDER, of Niagara, in the county of Wayne and State of Pennsylvania, have invented certain new and useful Improvements in Tire-Upsetters; and I do hereby declare that the following is a full, clear, and exact description of the same.

My invention relates to instruments of the class known as "tire-upsetters," intended particularly for stretching and upsetting wagon-tires when found too short or too long, so as to make them fit the fellies; and my invention consists in the combination, with a bed-piece, of a pair of oppositely-sliding bars, and a lever for simultaneously moving said bars in opposite directions, and a pair of pivoted adjustable tire-holders, all as will be more fully hereinafter described.

In the drawings, Figure 1 is a plan view with the lever shown in dotted lines. Fig. 2 is a section on line *x x* of Fig. 1. Fig. 3 is an edge view, showing the manner of attaching the tire-holder or vise.

In these drawings, A represents a flat metallic bed-piece, slightly curved from end to end, and having a central orifice to receive a bolt. Longitudinal dovetail grooves B B extend from each end of the bed-piece nearly to the central opening, and in these dovetail grooves slide bars C C, of a form in cross-section to snugly fit the grooves and work smoothly therein. The grooves and bars are formed on the same curve as the bed-piece. Near the inner end of each bar C is a short pin, 2, and these pins are so placed that they fit in curved grooves 3 4 in the lower face of a lever, D, when such lever is placed in position upon the central bolt, 1. Motion of the lever in either direction will move the bars either outward or inward, as the case may be, but always in opposite directions. The lever is secured upon the bolt by a nut, 5. The tire is carried by

holders or vises E E. The end of each of the bars C C is bored out, as shown, and the holder E is attached thereto by means of ears 7 7 and 45 a bolt, 8. The ears are rigidly attached to a sliding jaw, 9, which slides upon the shank 10 of a fixed jaw, 11. The continuation of the shank 10 is threaded, as at 12, and carries a grip or handle, F, having an interior thread, by 50 means of which the handle may be advanced or retracted along the screw-shank. The lower end of the movable jaw 9 has a projection, 13, against which the flat inner end of the handle bears, forcing the movable jaw toward the 55 fixed face. The device is thus adapted to different thicknesses of tire.

In the operation of this implement the tire, previously heated, is placed on the holders between the jaws, so that it bears against the flat 60 lower face of the bed-piece. Power is then applied to the lever, and the arms or bars moved outward, causing the metal to stretch. By turning in the opposite direction the metal will be caused to shrink.

My implement is a compact and powerful one, of simple construction, and very effective for the purpose for which it is intended.

Having thus described my invention, what I claim is—

In combination with the sliding bars and operating-lever, the tire-holders pivoted to such sliding bars, and having the fixed jaw, the movable jaw, the threaded shank, and the screw grip or handle, all substantially as described.

In testimony whereof I have hereunto signed my name, in the presence of two witnesses, this 5th day of November, 1881.

ROBERT E. ALEXANDER.

Witnesses:

WILLIAM WRIGHT,
T. H. BIGELOW.
